UNITED STATES PATENT OFFICE.

MINOT C. BLEST, OF HEGEWISCH, ILLINOIS, ASSIGNOR TO PRESSED STEEL CAR COMPANY, OF PITTSBURGH, PENNSYLVANIA, A CORPORATION OF NEW JERSEY.

DOOR-OPERATING MECHANISM.

1,160,828.

Specification of Letters Patent. Patented Nov. 16, 1915.

Application filed December 13, 1912. Serial No. 736,540.

To all whom it may concern:

Be it known that I, MINOT C. BLEST, a citizen of the United States, residing at Hegewisch, in the county of Cook and State of Illinois, have invented certain new and useful Improvements in Door-Operating Mechanism, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to those skilled in the art.

An object of the present invention is to provide a door operating mechanism for dump cars which will prevent the doors, when closed, from opening accidentally due to the heavy shocks to which a car is subjected, and to produce this result in a more positive manner than has hitherto been done.

Another object of the present invention is to provide a door operating mechanism in which the connections between the operating member and the doors are composed of a plurality of single bar links, which links are so connected together as to provide for movement of the same in either direction.

A further object of the present invention is to provide door operating mechanism in which the main door supporting member is so mounted that it will operate in a direction longitudinally of the car and is also operatively connected to the doors in such a manner as to allow the doors to drop away from the center sills.

A still further object of the present invention is to provide a dump car with a longitudinal ridge of a novel form which is adapted to protect the door operating mechanism from damage by the lading, and which will not reduce the cubic capacity of the car to any great extent.

In the drawings Figure 1 shows a plan view of a car, portions of the sides and longitudinal ridge being broken away to more clearly show the improved door operating mechanism mounted thereon; Fig. 2 shows a longitudinal sectional view on the line 2—2 of Fig. 1; Fig. 3 shows a cross sectional view on the line 3—3 of Fig. 1, and Figs. 4, 5 and

6 are detail views of portions of the door operating mechanism, while Figs. 7, 8 and 9 are similar views of a modification. Fig. 10 is an enlarged sectional view taken on the line 10—10 of Fig. 5.

Referring now in detail to the drawings, in which like reference characters refer to like parts and in which:

1 indicates the center sills which may be of any suitable form, 2 the car sides, 3 the end plate, 4 the sloping end hopper floor plates, 5 the cross ridge which may be of any suitable construction, and 6 indicates the sloping side hopper floor plates, which may be lapped over and secured to the sloping end hopper floor plates 4 at one end, and to 70 the crossridge plates 7 at the other end.

8 indicates the longitudinal ridge which comprises two plates having flanges along their top edges which are riveted or otherwise suitably secured together. Each one of these plates has two portions which slope downwardly and outwardly at different angles from the longitudinal center line of the car and where the lower outwardly sloping portion ends the plate is sloped downwardly 80 and inwardly and is secured to the web of the center sill. This ridge plate is also bent along its bottom edge in such a manner as to prevent lading from lodging on the flange of the center sill. These longitudinal ridge 85 plates are also secured to the sloping end floor plates 4 and crossridge plates 7.

The lower edges of the end hopper floor plates 4, side hopper floor plates 6, crossridge plates 7 and the longitudinal ridge 90 plates define the load discharging openings 9 which are adapted to be closed by doors 10 which may be hinged along their outer edges to the side hopper floor plates 6.

11 indicates brackets which are secured 95 to the doors 10 and extend beyond the inner edges thereof, such extensions being provided with thickened or rounded end portions 12. These thickened or rounded end portions are provided with tapered 100 openings 13 through which the ends of the bolts 14 may be passed. These bolts are provided with shoe members 15 which have curved surfaces 16 and are adapted to engage with and move freely on the surfaces 105 17 of the brackets 11 when the doors are operated. To hold the shoe members 15 in engagement with the bracket 11 the ends

of the bolts are provided with any suitable securing means such as nuts 18.

The upper or eye portions 19 of the bolts 14 are adapted to fit loosely in the jaws 20 formed in the link members 21 and may be operatively connected thereto by pins 22. These link members are also provided with top portions 23 which are adapted to fit loosely in the jaws 24 formed in the members 25 and may be operatively connected thereto by pins 26. The members 25 are also provided with jaws 27 at their upper ends, such jaws being disposed at right angles to the jaws 24 and adapted to receive the ends 28 of the members 29, said ends and members being operatively connected together by pins 30. The members 29 are perforated at 31, such perforation being adapted to receive pins 32 which operatively connect the said members with the arms 33 of the member 34. The member 34 is also provided with a sheave portion 35 for the accommodation of the operating chain 36, and to which portion 35 the arms 33 are integrally connected by walls 37. These arms besides being connected to the sheave portion 34, are connected to each other at their top portions by webs 38, and at their bottom portions are provided with laterally extending projections or trunnions 39, which may be journaled in bearing members 40 secured to the center sills 1.

41 indicates the operating shaft which may be of any suitable section and which may be journaled at one end in bearing members 42 secured to the car at or near the side thereof, and at the other end may be journaled in bearing members 43 secured to the center sills 1. This operating shaft 40 at the end nearest the side of the car is provided with the ordinary ratchet and locking mechanism, and at the other end portion intermediate the center sills 1, it is provided with a chain winding worm 44 to which the free ends of the chain 36 are secured. This chain besides being secured to the worm 44 extends to and is secured at substantially its central portion to the lugs 45 formed integral with the sheave portion 35.

When the doors 10 are in closed position the link members connecting the arms 33 and the brackets 11 may be at or slightly beyond the dead center of the sheave portion 35, as shown in Fig. 5, so that the weight on the doors will tend to automatically retain the doors in closed position.

All the parts of the mechanism having been described, the operation of the same may be described as follows: Assuming the doors to be closed and the car loaded with coal, the operator turns the operating shaft in the direction of the arrow in Fig. 1, which causes the chain 36 to pull the arms 33 and the links connected thereto away

from the dead center of the sheave portion 35; thus allowing the doors to drop by gravity.

In the modified form of the door operating mechanism the member 46 is similar to the member 34 shown in the preferred form, with the exception that the arms 33 are made shorter than those shown in the preferred form and the pin 32 is passed therethrough at a point nearer the projections 39 than in the preferred form.

In the modified form the link members 21 and 29 are both identical with those of the preferred form, while two link members 47 and two link members 48 are provided in the modified form which take the place of the two link members 25 as used in the preferred form. The link members 47 are provided with jaws 49 which are adapted to receive loosely the ends of the members 29, such jaws and member 29 being operatively connected together by pins 50. The members 47 are also provided with jaws 51 which are disposed at substantially right angles to the jaws 49 and are adapted to be operatively connected to the flattened end portions 52 of the link members 48 by pins 53. The lower ends of the link members 48 are provided with jaws 54 in which the top portions 23 of the members 21 fit loosely and are operatively connected thereto by pins 22.

It will be seen that the principle of automatically retaining the doors in closed position is the same in both the preferred and modified forms of the invention and it will also be seen that the operation of the mechanism in opening and closing the doors is substantially the same.

Having thus described my invention, what I claim as new and desire to secure by Letters Patent is:—

1. In a dump car, the combination with the center sills of a pair of doors hinged to said car, the free ends of said doors contacting with the bottom flanges of said center sills, a sheave member mounted between said sills, arms on said sheave member, links connecting said arms with said doors, an operating shaft and flexible means between said operating shaft and sheave member for operating said arms. 115

2. In a dump car, the combination with the center sills of a pair of drop doors hinged to said car and contacting with said center sills, brackets secured to said doors, said brackets extending beyond the free edges thereof, members loosely mounted within said brackets, a sheave member mounted between said sills, arms integral with said sheave member, link members connecting said arms and loosely mounted members, an operating shaft, and flexible means secured to said shaft and sheave member for operating said arms. 125

3. In a dump car, the combination with the center sills, of a pair of doors hinged at the sides of said car, the free ends of said doors contacting with said center sills, a 5 sheave mounted between said sills and bar link means connecting said doors and sheave.
4. In a dump car, the combination with the doors hinged at the sides thereof, of 10 brackets secured to said doors, center sills, a sheave member mounted between said sills, bar link members connecting said brackets with said sheave member and means for operating said sheave member.
- 15 5. In a dump car, the combination with the center sills of drop doors hinged at the sides of said car and contacting with said center sills, a sheave member adapted to be operated in the direction of the length of 20 the car mounted between said sills, means operable transversely of the car connecting said doors and sheave member and means for operating said sheave member.
- 25 6. In a dump car, the combination with the center sills of drop doors hinged at the sides of said car and contacting with said center sills, a sheave member adapted to be operated in the direction of the length of 30 the car mounted between said sills, arms on said sheave member, bar link members operable transversely of the car connecting said doors and sheave member, an operating shaft and flexible means operatively connected to said shaft and sheave member for 35 operating said arms.
7. In a dump car, the combination with
- a drop door hinged thereto, of a bracket on said door, said bracket having a thickened end portion, a member loosely mounted in said thickened portion, a shoe on said member adapted to contact with and move freely on said thickened portion, center sills, a sheave member mounted between said sills, means operatively connecting said loosely mounted member and sheave member, an 40 operating shaft and means connecting said shaft and sheave member for operating said doors.
8. In a dump car, the combination with drop doors, of brackets on said doors, members loosely mounted in said brackets, shoe members on said loosely mounted member adapted to contact with and move freely on said brackets and means for holding said doors in contact with said brackets.
- 45 9. In a dump car, the combination with the center sills, of a pair of drop doors hinged at the sides of said car, the free edges of said doors being adapted to contact with said center sills, a sheave member arranged between said sills at substantially the transverse center line of said doors, adapted to operate in the direction of the length of the car, links connecting said doors and sheave 50 operable transversely of the car, and means for operating said sheave member.

In testimony whereof I affix my signature in presence of two witnesses.

MINOT C. BLEST.
